UNITED STATES PATENT OFFICE.

THEODORE EDWARD SMITH, OF WEEHAWKEN, NEW JERSEY.

CIRCULATING APPARATUS FOR REFINING.

No. 829,356.

Specification of Letters Patent.

Patented Aug. 21, 1906.

Application filed March 26, 1906. Serial No. 308,117.

To all whom it may concern:

Be it known that I, THEODORE EDWARD SMITH, a citizen of the United States, residing at Weehawken, in the county of Hudson and State of New Jersey, have invented certain new and useful Improvements in Circulating Apparatus for Refining, of which the following is a specification.

My invention relates to improvements in circulating apparatus for the refining, oxidation, and similar treatment of compounds which are treated in fluid form, either in suspension, solution, or otherwise, such as occurs in the drying of edible oils and fats, the deodorization of cotton-seed oil after bleaching, the oxidation of linseed-oil, and the refining of various compounds in similar manner, in which the commercial treatment of the compound requires that it be handled in relatively large quantities, and the end desired is attained or facilitated by the surface exposure of the entire mass as rapidly and constantly as possible.

The purpose of my invention is to provide an apparatus whereby such fluid compounds may be handled in relatively large bodies, and so as to provide a substantially complete and rapid circulation of the entire body in such a manner that the entire body will be brought to the surface and superficially exposed in a minimum of time with a small expenditure of power and with a simply-constructed and readily-installed apparatus and that such superficial exposure will be continuously repeated so that the treatment to which the fluid mass is subjected will be completed in a very short time.

Another object of my invention is to provide mechanical means for establishing a rising and a return current in a tank, whereby the different ingredients contained in the tank will be brought into intimate molecular contact and with a minimum of mechanism, such as is requisite, for example, in the refining of cotton-seed oil, as is hereinafter set forth.

These and such other objects as may hereinafter appear are attained by my invention, one embodiment of which is shown in the accompanying drawings, in which—

Figure 1 is a vertical sectional view of a typical tank for the drying of edible oils and fats, and Fig. 2 is a view on the line 2.2 of Fig. 1 looking in the direction indicated by the arrows.

A is the tank, having mounted therein a

shaft B, carrying a propeller C. The shaft B extends through a hollow shaft D, which carries a propeller E at its lower end and is provided at its upper end with a gear-wheel F, while the shaft B is provided with a gear-wheel G. These gear-wheels are rotated in opposite directions by a gear-wheel H, which meshes with the gear-wheels F and G, the gear-wheel H being secured to the shaft I, which is driven in any suitable manner. The propellers C and E are arranged so that their blades are oppositely pitched and are arranged in relation to each other in the manner which I shall hereinafter describe.

The action of a propeller rotated at the bottom of a tank and in a fluid body and in a direction to cause an upward circulation of the fluid is such as I have demonstrated by experiments, as to cause the fluid to flow upwardly and outwardly, the lateral flow depending upon the pitch of the propeller-blades, but whatever the pitch may be so long as there is any pitch to cause an upward flow of the fluid such pitch will cause a lateral flow, with the result that there is always a very limited upward circulation of the fluid. Consequently unless the tank is very shallow the operation of the propeller will be merely such as to cause the fluid to rise slightly and then to flow in a curve toward the side of the tank and then downwardly. Consequently a large propeller may be rapidly rotated in a tank without causing any appreciable superficial agitation, and so without facilitating the superficial exposure of the contents of the tank while the initial rotation of a single propeller in a tank of fluid may result in some slight vertical agitation the lateral movement caused by the rotation of the propeller will shortly so dominate the vertical movement that the entire contents of the tank will take on a rotary movement with no appreciable or useful vertical circulation. If, however, a second propeller be arranged above the first propeller with its blades having an opposite pitch, the two propellers being rotated in opposite directions so as to cause an upward movement of the contents of the tank, the second propeller will catch the current rising from the first propeller as it begins to diverge toward the side of the tank and will tend to cause such diverging current to diverge in the opposite direction. When advantage is taken of this fact by arranging the propellers in accordance with my invention, the resultant of the opposing action of these

two propellers will be a substantially vertical current of sufficient force to carry the fluid from the propellers to the surface, along which it will flow toward the side of the tank and 5 thence downwardly to the propellers. Consequently the entire contents of the tank will be rapidly brought to the surface and given the extensive superficial exposure which is so desirable to the ends sought to be attained by 10 my invention. The relations of the propellers to each other will vary according to the diameter of the propeller-wheel and according to the pitch of the propeller-blades.

By experiment and practical demonstration 15 I have found that with a tank of the shape shown in the drawings, constructed twelve (12) feet in diameter and ten (10) feet deep to the cone with a cone two (2) feet deep, which is the standard size for holding 20 sixty thousand (60,000) pounds of cotton-seed oil, and using eighteen (18) inch propellers having the blades at an ordinary or standard pitch the best results are attained by locating the propellers one and a half (1½) 25 inches apart—that is, one-twelfth ($\frac{1}{12}$) of the diameter of the propeller-wheels. It will thus be seen that my invention differs radically from those devices the purpose of which is merely to stir, beat, mix, or agitate 30 the contents of a receptacle, where the stirring or beating devices substantially occupy the entire interior of the vessel.

I provide my mechanical device for the purpose of establishing a vertically-moving 35 column of the fluid contents of the receptacle, and preferably a column which shall rise centrally, so as to carry to the surface the fluid contents which lie deep down in the receptacle, and thus establish a circulation 40 which shall result in bringing the entire contents to the surface for the purpose of evaporation in a relatively short time. I am therefore enabled to use a device which may be small with relation to the entire apparatus 45 and which serves merely to start the vertical column, preferably at the bottom of the vessel, in such a manner that this mechanically-established column will continue to rise until the surface of the fluid contents 50 of the vessel is reached.

To attain the best results, it is important that the propellers have the proper vertical adjustment with relation to each other and have such a number of arms or blades that 55 there will be no opportunity for the fluid to be at rest between the propeller-wheels and not opportunity for any substantial lateral movement. I find, therefore, that propeller-wheels having four blades are most satisfactory, although three-bladed wheels may be used if the blades are so proportioned that the space between the blades of the propeller-wheel is but slightly greater than the width of the propeller-wheel blades.

Applying my invention, for example, to 65 the refining of mineral oils or to the drying of edible oils and fats, such as high-grade lard or lard-oil or cotton-seed oil, the operation will be as follows: In the manufacture of lard-oil, as is well known, after the lard-oil 70 has been pressed out of the lard it contains a considerable quantity of water, which must be eliminated, for a very slight percentage of moisture remaining in lard or lard-oil will sour the lard or lard-oil.

When a tank is filled with lard-oil containing such moisture, the water being of greater specific gravity will of course tend to settle 80 toward the bottom of the tank; but there will be no clear line of separation unless the tank is allowed to stand for a longer period than is consistent with commercial methods. Consequently the water is to a considerable extent held in suspension in the oil, especially in the lower part of the tank. If it is sought 85 to distil off the water by heat, the tank must be subjected to sufficient heat to boil the water and to force it through the overlying body of lard-oil; but this cannot be done, as the quality and flavor of the lard-oil will be affected 90 by a temperature much in excess of 140° Fahrenheit; but with my invention as the propellers are set in operation the propeller C, which is nearest the bottom of the tank, will start the water and oil in an upward current, and as that current begins to diverge 95 toward the sides of the tank the propeller E will take it up and tend to send it in the opposite direction. The resultant of the action 100 of these two propellers is the vertical current, (shown by the arrows in the drawings,) which carries the water to the surface of the tank, where part of the water is evaporated and part returns downwardly and is carried by the sides of the cone back to the 105 propeller C, which again starts the water upwardly. The result is that in a very short time and without the use of any high temperatures the water will be entirely evaporated and the oil may be drawn off free from 110 moisture and ready for use as a high-grade oil. In the manufacture of lard of high grade this same result may be attained, sufficient heat only being used to keep the lard in fluid condition.

In the manufacture of cotton-seed oil it is well known that after the oil has been bleached by the use of fullers' earth it has an exceedingly disagreeable odor, due to certain volatile elements. Here we have a product 120 which cannot be subjected to a high temperature for a long period without deterioration; but by means of my invention the entire contents of a tank will be rapidly brought to the surface in a short time, and in connection with refining by steam in a familiar manner the oil will be quickly deodorized without impairing the quality.

In the manufacture of linseed-oil where the tank is filled with a mixture of pressed oil and some oxygen-furnishing element, such as manganese or lead dioxid, for the production 5 of "boiled oil" by the oxidation of the pressed oil the process is facilitated by my invention, which rapidly and repeatedly exposes the entire contents of the tank to the oxygen of the atmosphere in a relatively short period.

In the refining of cotton-seed oil it is well known that caustic soda is commonly used and that the rapidity and efficiency of the process of refining is largely dependent upon the intimate intermingling of the caustic soda with the cotton-seed oil. Because of the differences of specific gravity between the soda and the oil there are difficulties in bringing about this intimate intermingling of these elements, and while agitating devices have 15 been used they are not practical in connection with deep tanks of large capacity, for the reason that the soda is not brought to the surface, and so will not be intermingled with the contents of the upper portion of the tank; 20 but by means of my invention the contents of the bottom of the tank, whether it be caustic soda or anything else, will be brought directly to the surface, whence it will diverge from the center and descend, causing a 25 constant, rapid, and intimate intermingling of the elements and a consequent hastening of the process of refining and with much better results. In such refining of cotton-seed oil it 30 is necessary to remove the free acid, resinous gums, coloring-matter, &c. To accomplish this result, caustic soda is added to the crude oil. The caustic soda combines with these undesirable elements to form "foots" or soap-stock, which is a compound soluble in 35 water which forms at first in minute particles—say of the size of a pin-point. As the agitation of the mass continues these pin-points form nuclei which gradually increase in size and are precipitated. In this process it is essential that the caustic soda shall be brought 40 into intimate contact with every molecule of the oil. Hence the necessity for some means of carrying the particles of caustic soda up through the entire mass of the oil, although 45 the soda is much heavier than the oil. The more perfectly this is done and the longer it is continued the clearer the oil becomes and the higher its market value. When the cotton-seed has been on storage for some time, 50 the quantity of coloring-matter is greatly increased and it becomes generally impossible with present methods to make a high-priced oil therefrom. This is for several reasons. If, for example, a device is used with a relatively 55 large number of mixing or beating arms which churn and agitate the entire mass of oil and caustic soda, the operation can be continued for only a short time, because the beater-arms will break up the particles of 60 foots or soap-stock after they have at-

tained a certain size and the effect of this breaking up of such particles is to cause the reabsorption of the coloring-matter, and the oil becomes an "off" oil which then cannot be refined into a high-grade oil. If, on the other hand, the agitation is stopped before this breaking up of the foots takes place, the result is not only that the refining is stopped before the best results are attained, but the foots remain in such small particles that they remain largely in suspension in the oil. If the oil is washed with water to precipitate these suspended particles, they will be largely dissolved by the water and return into the oil, thus affecting its color. If 70 filters are relied upon, these small particles will collect on the filter-bags and the color will go back into the oil. Not only so, but the presence of such mechanism in the refining-tank provides numerous places of lodgment for the particles of foots which are large enough to be precipitated. Then when the oil is drawn off from the tank these particles are dislodged by the flow of the oil and are carried by the oil to the filter-bags, where 75 they lodge and cause the color to go back into the oil. My device is therefore particularly useful in the art of refining cotton-seed oil, for while I provide means whereby the caustic soda is repeatedly brought into intimate 80 contact with every molecule of the oil from the bottom to the top of the tank I attain this result with such simple mechanism that there is practically no tendency to mechanically break up the particles of foots. Consequently I am enabled to continue the circulation of the caustic soda through the oil until all of the free acid, resinous gums, coloring-matter, &c., are eliminated so far as it is 85 possible for the caustic soda to attain this result. At the same time this prolonged agitation results in increasing the particles of foots to such size that they are all precipitated and the oil is entirely free therefrom. This result, I believe, has never before been 90 attained.

Owing to the location of my propellers at the bottom of the tank, and especially in view of their small size, and foots which lodge thereon do not interfere with the drawing off 95 of the clear oil from the tank.

As indicating the utility of my invention I have with an apparatus, as previously described, comprising a sixty-thousand (60,000) pound tank and a pair of eighteen (18) inch 100 propellers, perfectly dried sixty thousand (60,000) pounds of cotton-seed oil in three hours, and with a two-horse-power motor, at a temperature of not to exceed 140°, thereby producing a choice quality of what is commonly known as "salad-oil" or "butter-oil," 105 whereas with the best other apparatus now known there is no process for drying these high grades of oil, which must not be subjected to a temperature to exceed 140°, with 110

the exception of the universal practice of allowing such oils to separate from the water by gravity, assisted by a sprinkling of salt brine in shallow tanks, such process for sixty 5 thousand (60,000) pounds of oil requiring between two and three days, after which the clear oil is drawn from the top of the tanks, leaving in the tanks a body of water at the bottom superimposed by a mixed body of 10 water and oil, from which high-quality oil cannot be produced by processes now in use except by repeating the settling process.

In the manufacture of low-quality oils, where the question of flavor and quality is 15 not of importance, the water and oil are subjected to high temperatures, whereby the water is evaporated.

By my invention the salad and butter oils may be produced at low temperatures as rapidly as the low-grade oils can now be produced at high temperatures, while with my invention the manufacture of low-grade oil at high temperature will be greatly hastened.

I am aware that in other arts where the 25 end sought to be attained is mere agitation and mixing, devices have been used involving tanks containing oppositely-rotating beaters or mixers; but none of such devices, so far as I am aware, is constructed in accordance 30 with my invention, whereby the substantially vertical current is created, making it practical to carry the contents of a relatively deep tank directly to the surface of the tank and insuring the rapid and repeated superficial exposure of the entire contents of the 35 tank, which is such an important feature in the processes of manufacture to which I have briefly referred.

I do not, therefore, claim, broadly, a tank 40 provided with two oppositely-rotating propellers; but I do claim such a structure in

which the propellers are so arranged with relation to each other that the resultant of the action of the two propellers is to produce a substantially vertical current, whereby the 45 superficial exposure or intimate intermixture of the entire contents of the tank may be brought about.

I claim—

1. The combination with a tank, of a pair of 50 propellers of relatively small diameter in proportion to the diameter of the tank, said propellers being located in said tank adjacent to the bottom thereof and adjacent to each other, and means for simultaneously rotating 55 said propellers in opposite directions whereby a resultant local rising current is created.

2. The combination with a tank, of a pair 60 of propellers arranged to rotate upon a common axis and adjacent to each other, and having their respective blades pitched in opposite directions, said propellers being of small diameter in proportion to the diameter of the tank, and means for simultaneously rotating said propellers in opposite directions whereby a 65 resultant local rising current is created centrally of the tank, and a descending current is induced at the side of the tank.

3. The combination with a tank, of a pair 70 of propellers arranged to rotate upon a common axis and adjacent to each other and having their respective blades pitched in opposite directions, the blades of said propellers being relatively short in proportion to the radius of said tank, and means for simultaneously rotating said propellers in opposite directions whereby a local vertical current and an induced return current are created. 75

THEODORE EDWARD SMITH.
